CIGARETTE DISPENSER

Filed Nov. 11, 1927

BY

G. L. Gaston
J. Ledermann
ATTORNEY

UNITED STATES PATENT OFFICE.

GEORGE L. GASTON, OF JERSEY CITY, NEW JERSEY.

CIGARETTE DISPENSER.

Application filed November 11, 1927. Serial No. 232,526.

The main object of this invention is to provide a container holding a number of cigarettes in which a mechanism is mounted which expels these cigarettes one at a time into the palm of the hand.

Another object of this invention is to provide a container having a door thereon on which a mechanism is mounted for expelling these cigarettes one at a time.

10 Still another object of this invention is to provide a cigarette dispenser having the form of a container and a pivoted door on which a mechanism is mounted for expelling the cigarettes one at a time and agitating the remainder of the cigarettes so that they can be easily received by the mechanism at a successive instance.

15 The above and other objects will become apparent in the description below, in which characters of reference refer to like-named parts in the drawing.

20 Referring briefly to the drawing, Figure 1 is a longitudinal sectional elevational view through the dispenser, showing a cigarette resting in the expeller saddle.

25 Figure 2 is a front elevational view of Figure 1.

30 Figure 3 is a longitudinal sectional elevational view similar to Figure 1, showing the expeller device in operative position.

35 Figure 4 is a fragmentary top plan view of the device with the cover removed therefrom to illustrate the construction thereof.

Referring in detail to the drawing, the numeral 10 indicates the base of a container. This base has a rear end wall 11 and side walls 12 and 13 which join the end wall. The side walls have longitudinal channels 14 formed in their adjacent faces, which serve as guides for ridges 15 which project from the sides of a cover 16. This cover is designed to close the container and keep the cigarettes contained therein in a pure, fresh, and wholesome condition. The opposite end portion of the container is also closed by a structure which consists of a pair of bars 17 and 18 in which channels are formed. These channels in the bars 17 and 18, together with channels which are formed in the side walls 12 and 13, receive the edges of a transparent glass plate 19 through which the interior chamber 20 of the container may be sighted. An inclined table 21 is mounted within the container and serves as a support for a number of cigarettes 22 which normally roll or

slide to the lowermost position on this table. Beneath the bar 18 a rectangular open space is formed in this particular end wall and this space is normally closed by a hanging pivoted door 23. This door has its greater weight below its pivotal point, located on the pins 24 and 25.

The door freely hangs in vertical position and closes the rectangular opening located in this end wall and aids in sealing the dispenser when the same is not in use. On the inner face of the door 23 a semi-circular expeller block 26 is mounted. This expeller block has a curved saddle 27 formed at its upper end. The surface of the curved saddle, which extends longitudinal of the block, is below the plane of the inclined table 21, and cigarettes poised upon the lower end of the table will readily fall into the saddle when this saddle is empty. Kicker legs 28 and 29 depend from the expeller block 26 and are adapted to pass into slots 30 formed in the table 21 when the door is rotated 90 degrees, as is illustrated in Figure 3. These kicker legs are adapted to lift the cigarettes and rearrange or agitate the same as a cigarette is being expelled. An inclined runway 31 is formed on the door between its upper end and the curved saddle 27.

35 The container is adapted to expel cigarettes one at a time from the compartment 20. This compartment may receive a package of cigarettes or even more. These cigarettes rest upon the inclined table 21 and roll down this table to its lowermost position. The tapering mouth formed between the lower end of the table and the bar 18 permits the dropping of one cigarette into the curved saddle 27 which hangs, and is mounted, on the side of the door 23. By causing the fingers to contact with the door 23 below its pivotal point and urging the lower end of this door inwardly with the aid of the fingers, in such manner that the palm of the hand is upturned, the door is rotated 90 degrees and this changes the position of the saddle 27 so that it then assumes a position at the side of the cigarette and causes the latter to roll down the incline 31 on the door and fall into the palm of the hand. During the time that this movement is occurring, the kicker legs 28 and 29 are raised above the surface of the inclined table and these kicker legs lift and gently agitate the cigarettes at the lower end of the inclined table and so rearrange the 110

same that upon the next rotating of the door 23 one cigarette will surely be in a position to fall from the table into the saddle.

It is to be noted that certain changes in 5 form and construction may be made without departing from the spirit and scope of the invention.

I claim:

1. In a cigarette dispenser, a container, a sight glass mounted in said container, an inclined table in said container, a pivoted door mounted in said container, an expeller mounted on said door comprising a semi-circular block, a curved saddle in said block receiving a single cigarette rolling from the lower end of said inclined table, said saddle being adapted to change its position in rotation of said door, grooved kickers depending from said block, said grooves forming a saddle for a single cigarette, said table having slots therein receiving said kickers when said door is rotated from the vertical to the horizontal said kickers rearranging and lifting said cigarettes remaining on said table.
2. In a cigarette dispenser, a container, a sight glass mounted in said container, an inclined table in said container, a pivoted door mounted in said container, an expeller mounted on said door comprising a semi-circular block, a curved saddle in said block receiving a single cigarette rolling from the lower end of said inclined table, said saddle being adapted to change its position in rotation of said door, kickers depending from said block, said table having slots therein receiving said kickers when said door is rotated from the vertical to the horizontal, said kickers rearranging and lifting said cigarettes remaining on said table, said door being pivoted near its upper end so as to hang in normally closed position.
3. In a cigarette dispenser, a container, a sight glass mounted in said container, an in-

clined table in said container, a pivoted door mounted in said container, an expeller mounted on said door comprising a semi-circular block, a curved saddle in said block receiving a single cigarette rolling from the lower end of said inclined table, said saddle being adapted to change its position in rotation of said door, kickers depending from said block, said table having slots therein receiving said kickers when said door is rotated from the vertical to the horizontal, said kickers rearranging and lifting said cigarettes remaining on said table, said door being pivoted near its upper end so as to hang in normally closed position, said door having an inclined runway merging with said saddle adapted to form a ramp for expelling a single cigarette. 60

4. In a cigarette dispenser, a container, a sight glass mounted in said container, an inclined table in said container, a pivoted door mounted in said container, an expeller mounted on said door comprising a semi-circular block, a curved saddle in said block receiving a single cigarette rolling from the lower end of said inclined table, said saddle being adapted to change its position in rotation of said door, kickers depending from said block, said table having slots therein receiving said kickers when said door is rotated from the vertical to the horizontal, said kickers rearranging and lifting said cigarettes remaining on said table, said door being pivoted near its upper end so as to hang in normally closed position, said door having an inclined runway merging with said saddle adapted to form a ramp for expelling a single cigarette, said saddle being positioned so as to cause said single cigarette in said saddle to roll down said inclined runway on the door and be projected into the presented hand of the operator. 75

In testimony whereof I affix my signature,
GEORGE L. GASTON.
